UNITED STATES PATENT OFFICE.

WILLIAM A. TIDWELL, OF INDIANAPOLIS, INDIANA.

MISSILE FOR TOY GUNS.

Application filed April 7, 1927. Serial No. 181,653.

This invention relates to a missile to be projected from a toy gun, and in particular to such a missile in the form of a rubber ball with an elastic string attached thereto, described in detail with reference to the accompanying drawing, in which—

Fig. 1, is a side elevation of the ball; and

Fig. 2, a sectional view on the line 2—2 in Fig. 1.

Like characters of reference indicate like parts in the two views.

The ball 5 is made preferably of sponge rubber in order that it may have sufficient weight to enable it to be projected for quite a distance, but to give it sufficient resiliency so that any object being struck by it will not be damaged as it might be were the ball solid rubber.

A hole is punched through the ball 5 on a diameter and the rubber string 6 is pulled through the hole from one side of the ball to have the knot or button 7 come through the hole and bear against the other side of the ball to resist the pulling of the string back through the hole.

The string 6 is molded in one piece with the button 7 integral on the one end and an eye or loop 8 molded in the other end, the string itself being circular in cross section.

Hollow rubber balls have been employed heretofore with a string much smaller in diameter than the string 6 attached thereto by punching two holes closely together in one side of the ball, passing the end of the string in one hole and out the other and then tying the end back onto the string itself. Such an attachment is not satisfactory since the thin wall of the ball will tear out or the string break or become untied as it is extremely difficult to tie a rubber string with any degree of permanence. Moreover, the string to be attached in the heretofore manner necessarily had to be small in diameter to be so tied, and the string by reason of such small diameter could not be stretched sufficiently to impart sufficient initial velocity to the ball to project it to any appreciable distance.

By the method of attachment I employ, I can use the string 6 having a comparatively large diameter so that it does not have to be stretched out so far as the heretofore smaller string to give the same impetus to the ball, and there is no knot to become untied. While the button 7 by itself prevents the slippage of the string 6 through the ball 5, the string is gripped tightly by the spongy rubber throughout its entire length through the hole in the ball, the hole initially being much smaller in diameter than that of the string.

The eye 8 being molded in the string also eliminates the heretofore customary difficulty encountered in keeping a loop tied in the end. This eye 8 is designed to be hooked over a projection of the gun (not shown) so that the string may be stretched by pulling the ball 5 back to be positioned back on the gun at some point suitable for quick release. The string 6 can of course be molded integrally by one end to the ball 5.

I claim:

1. A rubber ball, an elastic string, said string being passed entirely through the ball by one end, and a button on said end to contact the ball said ball being formed of sponge rubber and gripping said string throughout its length through the ball.

2. A missile comprising a rubber ball, an elastic string of comparatively large diameter, a button on one end of the string, and a loop on the other end of the string, said string being attached to the ball by being pulled by the button end through a relatively small hole through the ball from one side to permit the button to bear against the ball from the other side of the ball and said ball being formed of sponge rubber and compressively gripping that portion of the string passed through the ball.

In testimony whereof I affix my signature.

WILLIAM A. TIDWELL.
